DESIGN FOR A MAIL BOX

Wilbur B. Driver, East Orange, N. J.

Application November 25, 1939, Serial No. 88,483

Term of patent 14 years

To all whom it may concern:

Be it known that I, Wilbur B. Driver, a citizen of the United States and a resident of East Orange, in the county of Essex and State of New Jersey, have invented a new, original, and ornamental Design for a Mail Box, of which the following is a specification, reference being had to the accompanying drawing, forming part thereof.

I claim:

The ornamental design for a mail box, as shown.

WILBUR B. DRIVER.
